[57] CLAIM

The ornamental design for an infant carrier, as shown and described.

DESCRIPTION

FIG. 1 is a left rear perspective view of an infant carrier showing my new design;

FIG. 2 is a left front perspective view thereof;

FIG. 3 is a rear elevational view thereof;

FIG. 4 is a front elevational view thereof;

FIG. 5 is a top plan view thereof;

FIG. 6 is a right side elevational thereof; and

FIG. 7 is a bottom plan view thereof.

The left side elevational view is a mirror image of the right side shown in FIG. 6. The loose ends of the shoulder straps are shown in various positions in the drawing figures.
